CLAIM

The ornamental design for a packing box, as shown and described.

DESCRIPTION

FIG. 1 is a front, left and top perspective view of a first embodiment of a packing box, showing my new design; FIG. 2 is a rear, right and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is another perspective view of the packing box, shown in an unfolded configuration; FIG. 10 is another perspective view of the packing box, shown in an unfolded configuration; FIG. 11 is a front, left and top perspective view of a second embodiment of the packing box, showing my new design; FIG. 12 is a rear, right and bottom perspective view thereof; FIG. 13 is a front elevation view thereof; FIG. 14 is a rear elevation view thereof; FIG. 15 is a left side elevation view thereof; FIG. 16 is a right side elevation view thereof; FIG. 17 is a top plan view thereof; FIG. 18 is a bottom plan view thereof; FIG. 19 is another perspective view of the packing box, shown in an unfolded configuration; and, FIG. 20 is another perspective view of the packing box, shown in an unfolded configuration. The broken lines shown depict boundaries of the transparent film and form no part of the claimed design.

1 Claim, 20 Drawing Sheets
